APPARATUS FOR MAKING MOTTLED PAPER

Olof H. Hedstrom, Jr., Hartford City, Ind.

Application October 24, 1933, Serial No. 695,025

1 Claim. (Cl. 92—40)

The invention relates to a method of and a machine for making paper and more especially of paper with a mottled or variegated effect.

The invention consists in raining variegating liquid onto pulp while the same is being carried through a paper making machine upon the usual Fourdrinier wire so that the merging of these charges of pulp and liquid will produce a "cloud" effect or mottled or variegated surface to the sheet paper form.

An object of the invention is to provide a machine for producing mottled or variegated paper so that the finished paper will present a "cloud" effect, the machine being of novel construction so that the liquid delivered to the paper pulp conveyed through the machine will be rained upon the pulp and the quantity of such liquid maintained at determined level in its container, the liquid being any paper filler of high opacity such as zinc oxide, titanium oxide, their sulphides, or asbestine, suspended in water, either alone or with dye.

Another object of the invention is to provide a machine of the kind described so that a supply of fluid in a plurality of streams or drops will be directed onto pulp when traveling through the machine, in order to break up the continuity or even upper surface of this pulp, whereby the finished paper product will be possessed of mottled or variegated effect.

With the foregoing and other objects in view the invention consists in the features of construction, combination and arrangement of parts as will be hereinafter more fully described in detail, illustrated in the accompanying drawings, which disclose the preferred embodiment of the invention, and pointed out in the claim hereunto appended.

In the accompanying drawings:

40 Figure 1 is a side elevation of a paper making machine constructed in accordance with the invention and showing the manner of carrying out the method of producing mottled or variegated paper.

45 Figure 2 is a fragmentary top plan view.

Figure 3 is a fragmentary vertical longitudinal sectional view.

Figure 4 is a fragmentary elevation.

Similar reference characters indicate corresponding parts throughout the several views in the drawings.

Referring to the drawings in detail, A designates the usual Fourdrinier wire of a paper making machine, with the ordinary supporting beams therefor as the rollers 10, 11 and 12 and the

breast and couch rollers 13 and 14, respectively.

Coating with the wire A is the deckle strap 15 which runs over the wheels 16 and 17 and is in contact with the wire A. The pulp is flowed onto the wire A in the usual manner and is then conveyed through the paper making machine conventionally.

Located above the wire A is a trough 18 preferably the width of the wire and having the rounded bottom 19 with a discharge mouth 20 receded from one end, which is regulated or controlled by an adjustable gate 21. Into this trough 18 is received the fluid to be rained onto the pulp carried by the wire A for producing mottled or variegated paper in the finished product.

Leading from one side of the trough 18 at the selected point above the lowermost portion of the trough or its bottom 19 is an overflow leveling pipe 22 having the superposed branches 23 and 24, respectively, the lowermost branch being 20 provided with a cut-off valve 25 and such branches open into the trough 18. The pipe 22 opens into a tank 26 carrying the supply of fluid for the trough 18.

Located adjacent to the receptacle 26 is a fluid pump 27, the same having the in lead 28 extended into the receptacle 26 and the out lead 29 opening into the trough 18 so that a forced feed of the fluid from the receptacle 26 to the trough 18 can be had in the operation of the pump 27.

The trough 18 is carried by the supports 30 elevated from the wire A.

Working within the trough 18 is a rotary brush 31 having the prongs 32, these being staggered with respect to each other, and the axle 33 of the brush is suitably journaled and operated from a power source, the prongs being adapted to enter the liquid within the trough 18 at varying depths to produce heavy or light effect in the mottling or variegating operation of the machine, the level 40 of the liquid within the trough 18 being controlled by the several overflow branches 23 and 24 of pipe 22. The gate 21 when raised or lowered will vary the total amount of raining of the liquid onto the pulp upon the wire A. This liquid as contained within the trough 18 may be any paper filler of high opacity, such as zinc oxide, titanium oxide, their sulphides, or asbestine, suspended in water, either alone or with dye, although the material constituting the liquid may be of any other substance that will produce the effect desired, such as beaten stock, or the like.

In the working of the machine, the pulp delivered by the wire A through the paper making machine will have rained thereon the liquid with

in the trough 18 and the raining of such liquid being had by the brush 31, so that the pulp will have intermingled therewith liquid, or such pulp will be diluted so that a mottled or variegated 5 effect to the finished product of sheet paper will be had.

The method consists in providing an irregularly mottled sheet of paper by having the mottles of 10 variations in color and opacity without variations in thickness or surface or printing qualities of the finished sheet of paper, the mottles being effected by raining liquid upon the pulp being conveyed on a Fourdrinier wire.

What is claimed is:

15 The combination with a paper pulp conveyor,

of a dished trough superposed with relation to the path of the conveyor, a receded portion at a discharge point of said trough, means for feeding colored fluid to the trough, a double branch overflow pipe leading from the trough to said means, the branches of said pipe opening into the trough at different elevations, a multiple pronged brush 5 rotatably fitted in the trough and confronting the receded portion in relatively close relation thereto, a pump having a lead-in from the said means and an outlet opening into the trough, and a gate adjustably related with the receded portion of the trough, the prongs of the brush being radially disposed and staggered with respect to each other.
